UNITED STATES PATENT OFFICE.

EGERTON A. BLISS, OF NEW YORK, N. Y.

DESIGN FOR A WATCH-CHAIN HOOK.

SPECIFICATION forming part of Design No. 11,858, dated July 13, 1880.

Application filed May 18, 1880. Term of patent 3½ years.

To all whom it may concern:

Be it known that I, EGERTON A. BLISS, of the city, county, and State of New York, have invented a new and original Design for Watch-5 Chain Hooks, of which the following is a full, clear, and exact description.

The nature of my invention is fully shown in the accompanying drawing, to which reference is made.

10 This invention relates to an improved design for a watch-chain hook; and it consists of a hook in the shape of a padlock, the body of which is ornamented in suitable manner.

In the drawing, A represents the body of 15 my improved watch-chain, which is made in the shape of a padlock with projecting top part, a. B is the hook portion or link of the same, which extends from one side of the projecting portion to the other.

20 The body A is divided into three panels by

two diagonal ribs or lines, b, which extend from the corners to the lower center point, said panels being ornamented in a suitable manner.

Having thus described my invention, I claim as new and desire to secure by Letters Patent—

The design for a watch-chain hook, consisting of a body, A, having a projecting top portion, a, and diagonal face-ribs b, and of a hook or link, B, extending from one side of the top 30 projection to the other, as shown and described.

In testimony that I claim the foregoing as my invention I have signed it this 11th day of May, 1880.

EGERTON A. BLISS.
